CASING FOR AN ELECTRONIC CALCULATOR OR THE LIKE

Terrell Oyama, Santa Clara, Calif., assignor to Fairchild
Camera and Instrument Corporation, Mountain View,
Calif.

Filed July 22, 1974, Ser. No. 490,538

Term of patent 14 years

Int. Cl. D18—01

U.S. Cl. D26—5 C

FIG. 1

FIG.2

FIG.3

FIG.4

FIG.5

FIG. 1 is a top perspective view of a casing for an electronic calculator or the like, showing my new design;

FIG. 2 is a top plan view thereof;

FIG. 3 is a right side elevational view thereof, the left side being substantially a mirror image thereof;

FIG. 4 is a front elevational view thereof; and

FIG. 5 is a rear elevational view thereof.

The bottom surface of the casing for an electronic calculator or the like is substantially flat and unornamented.

I claim:

The ornamental design for a casing for an electronic calculator or the like, as shown and described.
